SHOE AND METHOD OF SHOEMAKING

Morris Green, Boston, Mass., assignor to A. R. Hyde & Sons Company, Cambridge, Mass., a corporation of Massachusetts

Application October 12, 1935, Serial No. 44,717

3 Claims. (Cl. 12—142)

This invention relates to the art of shoe making and more particularly to the type of shoes known as "compo" shoes wherein the sole is secured to the upper by an adhesive.

5 Adhesive cements which have been developed during recent years are waterproof and of sufficient strength to make possible the satisfactory use thereof in securing a shoe sole to the upper. The cemented bond between the sole and upper is usually satisfactory when the sole is of a good grade of leather. When poor or medium grades of leather are used, however, the flesh side of the leather sole is liable to be surfaced by relatively long loose fibers which are apt to 10 pull away from the body of the leather under stress. Hence, some difficulty has been experienced in forming a strong cemented bond between shoe soles and the uppers where medium grades of leather have been employed for the soles.

It is an object of the present invention to provide simple but effective means for strengthening the bonding of the sole to the upper, regardless of the quality of leather used in the sole. 15 To this end, a line of stitching is run along the margins of the shank and forepart of the sole, the portions of the loops of stitching which are exposed on the upper face of the sole being adapted to be impregnated with the cement or adhesive material employed to cement the sole to the upper. When the sole is pressed against the lasted upper, these impregnated exposed portions of the loops of stitching are pressed into direct engagement with the over-lasted portions of the upper and form therewith a strong bond. Since the stitching goes through the sole, the entire sole is thus secured to the upper regardless of the quality of the flesh surface of the sole stock which is against the lasted upper.

20 If desired, a more effective bonding between the sole and upper may be secured, according to the invention, by stitching a strip of tape or other suitable material of sufficient strength along the margins of the shank and forepart 25 of the sole. This tape should be of a material such as a woven textile, adapted to adhere strongly to the kinds of cement customarily employed in the making of compo shoes. The tape, being anchored to the sole by the stitching which 30 goes through the sole, aids the stitching in firmly uniting the sole to the upper.

For a more complete understanding of the invention, reference may be had to the following description thereof and to the drawing 35 of which

Figure 1 is a fragmentary plan view of a shoe sole embodying the invention.

Figure 2 is a sectional view on the line 2—2 of Figure 1.

Figure 3 is a sectional view of a shoe including a sole such as is illustrated in Figure 2.

Figure 4 is a sectional view, similar to Figure 3, showing a slightly modified form of invention.

Figure 5 is a fragmentary sectional view showing a portion of Figure 4 on a larger scale.

Figure 6 is a plan view of a portion of a shoe sole embodying a modified form of the invention.

Figure 7 is a section on the line 7—7 of Figure 6.

Figure 1 of the drawing illustrates a shoe sole 10, preferably of leather, the flesh or upper surface thereof being shown on the drawing. After the sole has been cut to shape, a line of stitching 11 is run along the margins of the shank and forepart of the sole 10, this stitching being of loops of coarse thread extending through the sole so that portions of these loops are exposed on the bottom face of the sole and other portions are exposed on the upper face of the sole as indicated in Figure 1. Any preferred type of stitching, such as a lock stitch or a chain stitch, may be employed. After the line of stitching 11 has been made on the sole 10, a film 12 of liquid cement or adhesive material is applied to the marginal portion of the upper face of the sole 10 so as to impregnate the portions of the stitching loops exposed on the upper face and to cover the marginal areas of the upper face of the sole adjacent to the line of stitching. If desired, this adhesive may be allowed to dry and may be later activated by the use of a suitable solvent immediately prior to the application of the sole to a lasted upper.

Figure 3 illustrates in section a shoe including a sole 10 having stitching 11 as hereinbefore described, the sole being adhesively pressed against the upper 15 with its lining 16 so that the film 12 of adhesive and the impregnated portions of the stitching 11 are pressed directly against the over-lasted portion of the upper 15. This direct engagement of the stitching 11 with the over-lasted portion of the upper strengthens the bond between the sole and the upper, since the adhesion of the stitching to the upper is independent of the quality of the surface of the sole leather.

If desired, in addition to the stitching 11 in the sole, the over-lasted portion of the upper 15 may also be stitched as at 20, either before or

after the lasting operation, the stitching 20 being so arranged as to be directly opposite the stitching 11 in the sole when the sole is adhesively pressed against the lasted upper. The 5 firm cemented adhesion between the thread loops of the upper greatly strengthens the bond between the sole and the upper.

Additional strengthening means may be provided, if desired, as indicated in Figures 6 and 10. Prior to the stitching of the sole, a strip of 15 tape 25 may be applied to the marginal portions of the upper face of the sole so that the stitching 11 will mechanically anchor the strip 25 to the sole 10. The strip thus provides a wider 20 line of contact than the stitching alone for adhesive bonding with the lasted upper. The cement 12 which is applied to the margin of the sole assists the stitching in firmly anchoring the strip 25 to the sole, so that, when the sole is 25 pressed into adhesive contact with the lasted upper, the presence of the impregnated strip 25 greatly strengthens the bond between the sole and the upper.

While leather has been hereinbefore mentioned 25 by way of example as material for the sole 10, it is to be understood that the invention is not to be limited to that or any other material, but may include rubber, composition, or any other suitable sole material. It is evident that 30 various other modifications and changes may be made in the invention, without departing from the spirit or scope thereof as defined in the following claims.

I claim:—

35 1. A method of making shoes, which comprises stitching through a shoe sole along the

margins of the shank and forepart thereof, so that portions of the loops of stitched thread are exposed on the upper face of the sole, applying an adhesive to marginal portions of the upper face of said sole including the loops exposed thereon, and pressing said sole into adhesive contact with a lasted upper so that said exposed loop portions directly engage the overlasted portion of the upper. 5

2. A method of making shoes, which comprises 10 stitching through a shoe sole along the margins of the shank and forepart thereof, so that portions of the loops of stitched thread are exposed on the upper face of the sole, stitching through the portion of a shoe upper which is to be 15 over-lasting on the last, lasting said upper, and cementing the sole to the upper so that the stitching in the sole is in direct contact with and is cemented to the stitching in the over-lasting portion of the upper. 20

3. A shoe comprising an outer sole and an upper having a lasted portion, said outer sole having a line of stitching therethrough along the margins of the shank and forepart thereof to strengthen and reinforce the sole material, 25 portions of the stitching being exposed on the upper face of the sole, and a film of cement impregnating said exposed portions of the stitching and adhesively uniting said lasted portion with the upper face of the sole and with said 30 stitching, the stitching serving to strengthen the adhesive bond between the lasted portion and the sole and to secure the entire thickness of the sole to the lasted portion. 35
